UNITED STATES PATENT OFFICE.

LOUIS W. FARQUHAR, OF ST. LOUIS, MISSOURI.

SAFETY-GUARD FOR RAZORS.

1,138,649.

Specification of Letters Patent. Patented May 11, 1915.

Application filed May 11, 1914. Serial No. 837,766.

To all whom it may concern:

Be it known that I, LOUIS W. FARQUHAR, a citizen of the United States, residing at St. Louis, in the State of Missouri, have invented new and useful Improvements in Safety-Guards for Razors, of which the following is a specification.

This invention relates to a safety attachment for razors and comprises an adjustable 10 guard design to be removably and reversibly applied to the ordinary forms of razors.

An object of the invention is to provide a safety guard for razor blades of the ordinary type which is both simple in construction and economical to manufacture; that is effective in operation and easily and quickly applied to a razor blade whether the same be broad or narrow, heavy or light, said guard having self-holding means for retaining it in position upon the razor blade and is provided with a simple means for adjusting the guard relatively to the cutting edge of the blade to give the latter varying degrees of safety in shaving according to the 25 closeness of shave desired.

A further object of the invention is to construct the device in such way as to insure an equal distribution of the pressure on the back of the razor blade when the same is being adjusted forwardly in the guard.

A further object of the invention is to provide a very simple construction which particularly adapts the plates which form the body of the guard to be produced in a 35 single operation, as in a press.

The device includes means for adjusting the guard to the blade, and one of the objects of the invention is to provide an improved arrangement for supporting this adjusting means, and for attaching the same to the blade-presser which engages the back of the razor blade.

In the drawing which illustrates the preferred embodiment of my invention Figure 45 1 is a side elevation of the guard showing the same applied to a razor blade. Fig. 2 is a view similar to Fig. 1, but showing the reverse side of the guard. Fig. 3 is a vertical transverse section through the device upon 50 an enlarged scale, and showing the razor blade in position. Fig. 4 is a vertical section illustrating the preferred means for connecting the adjusting device to the member which presses the back of the razor 55 blade.

Referring more particularly to the parts,

10 and 11 represent two blade engaging members which are disposed opposite to each other, the upper extremities of the same preferably being formed with flanges 60 14 which are disposed opposite to each other, and which enable the two plates to be attached together by means of rivets 15 or other fastening means. Between the flanges the material of the plates is preferably offset 65 so that when the two offset portions come together they form guiding means in the form of a sleeve 16 for adjusting means preferably in the form of a screw 21, said screw having an enlarged head 21' facilitating its rotation 70 between the thumb and the forefinger. The plates 10 and 11 are relatively narrow at this point, and their side edges diverge so that the bodies of these plates are elongated in a longitudinal direction of the razor blade A to 75 which the guard may be applied. Just below the flanges 14 the plates are offset outwardly and oppositely so as to form two substantially parallel guide cheeks 12 and 13, and beyond these cheeks the lower edges 80 of the plates converge as indicated, the lower edge of the plate 10 being serrated and provided with a plurality of guard fingers 17, which preferably curve outwardly slightly. This plate 10 which carries the guard fingers is preferably longer than the plate 11. The ends of the plate 11 are preferably 85 slightly turned outwardly as indicated at 18. This arrangement facilitates the insertion of the blade in the guard.

It will be seen that the connected flanges 14 form a narrow strip or U-shaped neck uniting the two plates 10 and 11, and this neck gradually widens out at the cheeks 12 and 13.

Between the cheeks 12 and 13 I mount a blade-presser 19, which is preferably in the form of an elongated slightly bowed resilient strip or spring. The object of the bowed form is to enable the presser to exert its 100 pressure on the blade at its extremities 19' in order to distribute the pressure which is exerted by the adjusting screw in adjusting the presser toward the blade.

I prefer to connect the adjusting screw 21 to the blade presser in the manner indicated in Fig. 4. For this purpose I prefer to employ a screw 21 of tubular form, and through the bore of the screw I pass a swivel pin 20, the lower end of which passes through 110 the blade presser 19 at its middle point and is riveted to the same at 22, the upper end

of the said pin being riveted into a head 20', which may if desired be countersunk in the head 21' of the screw. This makes a simple swivel connection between the screw and 5 blade-presser, and preferably the pin 20 is rigid with respect to the blade-presser, so that there is a large wearing surface between the screw and the pin.

The plates 10 and 11 are resilient, and 10 tend to approach each other so that when applied to a razor blade as indicated their lower parts conform to and clamp the blade and offer a slight resistance to the advance of the blade in the guard by the adjusting 15 screw 21.

The guard is placed on the razor blade by an endwise thrust, the insertion of the blade being facilitated by the outwardly turned lips 18 at the ends of the plate 11.

20 It will be seen that the cheeks 12 and 13 form an effective guide for the blade-presser and prevent its rotating when the screw is rotated, and for this reason the width of the blade-presser is such that it fits neatly in the 25 space between the guide cheeks 12 and 13.

In order to insure that the pin 20 will be 30 rigid with the blade-presser when riveted, if desired, the countersunk opening in the blade-presser may be notched in a well understood manner.

After adjusting the guard to a blade, it may be removed therefrom at any time, replaced or reversed without need of further adjustment, there being no screw or other 35 fastenings to hold the guard on the blade, and but one adjusting screw which it is not necessary to touch when removing or replacing the guard.

If desired the screw threads in the sleeve 40 16 may be formed in the dies which form the plates 10 and 11, so that the threads are formed by the same operation that forms the plates, but if it is preferred not to form the threads in this way they may be cut in 45 the sleeve after the plates 10 and 11 have been riveted together.

The upper edges of the plates 10 and 11 do not extend as high as the back of the 50 razor blade and as the neck at which the plates are connected is narrow, no impediment is offered to a person shaving around the nose, ears, and upper lip.

It is understood that the embodiment of the invention described above is only one of 55 the many forms or embodiments the invention may take, and I do not wish to be limited in the practice of my invention, nor in my claims, to the particular embodiment set forth.

60 What I claim is:—

1. A safety guard for razor blades comprising a pair of elongated plates having a narrow connection therebetween, said plates having a neck near said connection with 55 substantially parallel sides, a presser strip

guided in said neck and between the sides thereof and adapted to engage at two separated points the back of a razor blade to which the guard is applied, said plates having converging portions beyond said neck 70 adapted to engage the sides of the razor blade, and a single adjusting screw between said separated points mounted in said narrow connection and imparting the adjusting force through said presser strip to the 75 razor blade.

2. A safety guard for a razor blade consisting of two plates adapted to engage the opposite sides of the razor blade, a blade-presser mounted between said plates, an adjusting member for moving said blade-presser toward the razor blade, said plates having oppositely disposed offset portions forming a guide engaging said adjusting means.

3. A safety guard for a razor blade consisting of two plates adapted to engage the opposite sides of the razor blade, a blade-presser mounted between said plates, a screw for adjusting said blade presser toward the razor blade, said plates having meeting flanges and each having an offset portion, said offset portion being oppositely disposed and forming a guide sleeve engaging opposite sides of said screw.

4. A safety guard for a razor blade consisting of two plates adapted to engage the opposite sides of the razor blade, a blade-presser mounted between said plates, a screw for adjusting said blade presser toward the razor blade, said plates having oppositely disposed offset portions forming a guide sleeve engaging said screw, and a swivel connection between said screw and said blade-presser.

5. A safety guard for a razor blade having means for engaging the sides of the razor blade, a blade-presser for engaging the back edge of the razor blade, a screw mounted in said guard for adjusting said blade presser toward the blade, said screw having a bore passing therethrough, and a pin connected with said blade-presser and passing through said bore to retain said screw in connection with said blade-presser.

6. A safety guard for a razor blade having means for engaging the sides of the razor blade, a blade-presser for engaging the back edge of the razor blade, a screw mounted in said guard for adjusting said blade presser toward the blade, said screw having a bore passing therethrough, and a pin connected with said blade-presser and passing through said bore to retain said screw in connection with said blade-presser, said pin forming a 120 swivel pin and having one extremity riveted to said blade-presser and the other extremity riveted over the end of said screw.

7. A safety guard for razor blades comprising a pair of connected plates, said 125

plates having oppositely disposed parts forming a neck with substantially parallel sides and having converging blade engaging members beyond said neck for engaging the 5 razor blade to which the guard is applied, a single adjusting screw having a threaded connection with said guard, and a resilient presser strip guided between the sides of said neck toward and away from the razor 10 blade and having a swiveled connection near its middle point with said screw and imparting the force from said screw to the razor blade at two widely separated points.

8. A safety guard for razor blades consisting of two connected plates adapted to 15 receive the razor blade therebetween, a single adjusting screw mounted in said guard, and a spring in the form of a presser strip

connected with said screw near the middle point of said presser strip, and adapted to receive a force exerted through said adjusting screw and impart the same through said presser strip to the razor blade at two separated points to force the blade outwardly, 20 said connected plates having elongated extensions converging toward each other, forming to the shape of the razor blade and resisting the outward adjusting movement of the blade by said adjusting screw.

In testimony whereof I have hereunto set 25 my hand in presence of two subscribing witnesses.

LOUIS W. FARQUHAR.
